UNITED STATES PATENT OFFICE.

REINHARD E. BARTELS, OF LYNN, MASSACHUSETTS.

APPARATUS FOR LOCATING SHANK STIFFENERS IN SHOE SOLES.

Application filed April 26, 1920. Serial No. 376,633.

In attaching rigid shank stiffeners to shoe soles, the forward end of the shank stiffener should be located a short distance back of or "below" the break line in order that the resiliency of the shoe at the break line may not be impaired and the shoe thereby ruined.

The shank stiffener is attached to the shank of the sole while the sole is flat and before it has been shaped to its final form, and for this reason it is difficult to judge when locating the stiffener, where the break line will be on the sole when the shoe is completed. Consequently, many soles have been spoiled by the location of the shank stiffener too far forward or too far back relative to the break line, in the first instance, destroying the resiliency of the sole at the break line, and in the second, throwing off the tread of the heel, either of which fault is undesirable from the standpoint of good workmanship, if not fatal to the usefulness of the shoe.

One object of my invention is to overcome these difficulties by producing a gaging apparatus, whereby the workman can quickly and accurately locate the shank stiffener on a sole of a given style and size.

Another object of my invention is to provide means whereby when the desired point, for the end of the shank stiffener, on a sole of one size of a certain style has been located, the corresponding point for any other size of that same style may be readily located.

A still further object is to produce mechanical means whereby the desired point in any given sole may be readily and accurately located.

A specific embodiment of my invention, by which the above objects may be accomplished, is illustrated on the accompanying drawings, in which—

Figure 1 is a plan view of my shank stiffener locating apparatus, with a sole shown thereon in dotted lines.

Figure 2 is a side elevation of the same.

Figure 3 is a transverse section on line 3—3 of Figure 1, showing the dovetailed connection of the slide with the plate.

Figure 4 is a longitudinal section on line 4—4 of Figure 1, showing certain details of the device.

Figure 5 is a view showing a shoe sole with a shank stiffener located on the shank thereof.

Figure 6 is a view showing a shank stiffener in perspective.

My apparatus may be used to locate any desired point on the sole of a shoe, but the particular use for which it is designed is to locate a point on the shank of a sole of given style and size at which the forward end of a shank stiffener, to be attached thereto, should terminate. In actual practice, this point is located on the sole, about one-fourth of an inch back of the break line, indicated at 29, Figure 5.

The accurate location of this point by mechanical means is made possible by the fact that the forepart 30 of the sole, i. e., from the toe to the break line, varies in length by approximately one-sixth of an inch for each change of full size of the shoe, regardless of style. Therefore, if a point is selected on the sole of a shoe of any known style and size, called for convenience the "selected sole", and it is desired to locate the corresponding point on a sole of a different size of the same style, called for convenience the "problem sole", one proceeds as follows: First, the distance from the toe to the break line is measured on the "selected sole", and then the distance from the break line to the point selected is added to or subtracted from this distance, according as the point lies behind or in front of the break line. Then one-sixth of an inch for each unit of size number by which the "problem sole" is greater than, or less than the size of the "selected sole", is added to or subtracted from the distance found above, as the case may be. This new distance will be the distance measured rearwardly from the toe at which the required point lies on the "problem sole".

As has been stated above, the object of my invention is to find such point on the sole, by mechanical means, and the mechanism by which it is accomplished will now be described in detail, referring to the accompanying drawings by reference numerals. After describing the details of the device, I will set forth the manner of its use in actual practice.

My invention as shown in the specific embodiment illustrated, comprises a plate 10. The rear end of the plate is recessed to receive a steel plate 12, which is fastened in place by means of screws 13, or other suitable securing means.

Located upon the upper face of the plate 10 are score lines 14 and 15, which lie diagonally across the face thereof, and cross at a point 16 on the longitudinal central line of

the plate. These lines are located toward the rear end of the plate, and at any suitable distance from the rear of the size scale, to be described. The angle at which lines 14 and 15 lie to each other may vary, but the adjacent angles which these lines make with the longitudinal line of the plate which passes through the point 16, must be equal. The purpose of these lines and of their position on the plate will appear later.

Slidably arranged on the forward end of the plate 10 is a gage or locating plate 17, the side edges 19 of which are beveled outwardly to fit slidably in the complementary undercut inner edge of guideways 20 and 21. These guideways may be formed integral with the plate 10, or, as shown, may be attached thereto by means of screws and extend from the forward end thereof, rearwardly along the edges for about half the length of the plate. The slide 17 is provided with a reentrant curved recess 18 in the edge thereof toward the rear of the plate 10. This recess may be of such contour and size as to receive the toe of a sole of practically any style or size which may be placed on the plate.

The guide member 20 may have a scale 22 cut on one of the side edges thereof, corresponding to the sizes of a shoe, say, from 1 to 16 inclusive, and the complementary locating plate has a similar scale 23 on its inner edge adjacent to the graded side edge of the location plate. The graduations of the scale on the guide member are so spaced that each full gradation is equal to the difference of length between the sole of one size of shoe and the next larger size, measured from the tip to the desired point, as stated above, one-sixth of an inch. Half grades, or half sizes, or any other fractional sizes may be indicated on this scale. The graduations of the scale 23 on the locating plate are arbitrary, and there may be as many to the inch as is found convenient; the only requisite is that they be sufficient in number, so that one of the graduations on the slide may come approximately opposite a gradation on the guide member, corresponding to the size of the shoe sole when a key number on the slide is being found. The scale which indicates size may be called the size scale, and the full grades thereof, size numbers or size grades.

Located on the guide member 21 is a clamping member adapted to clamp the locating plate 17 in adjusted position. This clamping member comprises a check nut 24 resting on the guide members 21, and a bolt 25 passing through the center thereof and screw-threaded into the guide member 21 and plate 10. This bolt is provided with a head 26 adapted to bear on the upper surface of the check nut to cause it to clamp the slide in position. The head of the bolt may be turned to and from clamping position by

means of the lever arm 27 extending therefrom.

A circular steel plug 28 is preferably counter-sunk into plate 10 at about the point 16 at which lines 14 and 16 cross as a center. 70 The shape of this member is immaterial, however, and the purpose of the plug 28, and of the steel plate 12, are to present hard, durable surfaces beneath the sole placed on the plate at the points at which the tines 75 which secure the shank support to the sole, pierce the leather and clinch. Wear on the plates at these points which would otherwise occur in the relatively soft metal of plate 10, is thereby prevented. These steel members 80 are not, however, essential parts of the invention, and may be dispensed with altogether. The plate 12 and the plug 28 may be made of tool steel, and may be referred to as wear plates.

The particular gradation of the locating plate 17, which comes opposite a gradation on the guide member for any given size, varies with the style of the shoe. In order to find this gradation for a given style, I first 90 select a last of a known size of the style in question, and measure the length of the fore part of the last, i. e., from the toe to the break line, and add to this, one-eighth to one-quarter of an inch for the overhang of the 95 sole, that is, the distance that the sole extends beyond the last after the upper is pulled over the last; and one-quarter of an inch for the distance back of the break line at which the forward end of the shank stiffener is preferably to be located. I then mark off this distance forwardly along the plate 10 from the point 16 where the lines 14 and 15 cross and set the location plate so that the apex of the reentrant curve or recess is 100 located at the forward end of the measured line, and clamp the locating plate in this position. The gradation on the locating plate which falls opposite the size number on the guideway 20, corresponding to the size number of the last selected, is marked as at X to form the reference line, and is taken to be the key number for the given style.

Inasmuch as the sizes of all styles vary by a fixed distance, as above indicated, the position of the location plate for any other size of the given style is determined by merely bringing opposite the key number X, as found above, the gradation indicating that size on the size scale 22. The scale 23 on 115 which the key number is located, may be known as the style scale, and the gradation thereon as style numbers, and may receive arbitrary symbols for the different styles. However, the style scale may be dispensed with altogether, and a mark made to indicate a key number for any given style when its location is determined by the above method. Or, for convenience, where a manufacturer works on only a limited number of 120 125 130

styles, the key number for each style may be found and permanently indicated on the locating plate as such.

To find the desired point at which the forward end of the shank stiffener is to be placed on a given size and style, all that is necessary is to bring the proper size number opposite the key number, as determined above, for that style, to place the sole on the plate with the toe touching the slide at the apex of the recess, and the desired point at which the forward end of the shank stiffener is to be located on the sole will then lie at the intersection 16 of lines 14 and 15, whereupon, the operator may place the shank stiffener in place, judging sufficiently accurately with his eye, the location of the shank stiffener, by observing the position of line 14 or 15, according as the sole is for a left or right shoe, and may secure the shank stiffener in place thereon without further measurement. The shank stiffener is laid to register with the median line of the heel end of the sole.

This application contains claims specific to the construction herein illustrated and described and generic to these and other constructions such as are specifically disclosed and claimed in my United States Patents Nos. 1,493,950, granted May 13, 1924; and 1,565,702 and 1,565,774, both granted December 15, 1925, the subject matters of which were divided out from this application. The term "shoe soles" is intended to include shank pieces as well, and various changes and modifications may be made therein without departing from the spirit of the invention as set forth in the statement of invention and the claims hereto appended.

I claim:

1. In a device for locating a desired point on a sole for a shoe of any given size and style, a plate having indicated thereon a fixed point, a locating plate slidable on said plate, and guideways in which said locating plate slides, one of said guideways having a scale comprising gradations spaced apart a distance equal to the difference of the length of soles due to unit increase in the size thereof, said plate having diagonal lines crossing at the fixed point.

2. A device of the class described comprising a plate for supporting a shoe part and having means to define the location of a shank stiffener, and a gage adjustable on said plate and engageable with one end of the shoe part said gage having a scale thereon

corresponding to different sizes of shoe parts and there being a fixed reference line cooperating with said scale, said scale and line being so related as to correctly locate by said defining means the position of a shank stiffener for the size indicated on said scale when the shoe part is placed in position against said gage.

3. A device whereby a desired point on a shoe sole at a predetermined distance from the break line may be found for any size of a given style of shoe, which comprises a plate upon which the sole may be placed, said plate having a marked fixed point, 70 guide members on said plate, and a slide member adapted to slide between said guide members, said plate having a scale, the gradations of which are spaced apart a distance equal to the unit difference in length of the 75 forepart of a shoe sole for each unit increase in the size of the soles and with which said slide member may be brought into determined relation.

4. A device of the class described comprising a plate for supporting a shoe sole and having means to define the location of a shank stiffener relative to said plate, and a gage adjustable on said plate and engageable with one end of the sole, said gage having a scale 80 thereon corresponding to different sizes of soles, there being a series of fixed reference lines each corresponding to a certain style of shoe, said scale and lines being adapted to cooperate to correctly locate said gage on said 85 plate whereby the proper position of the stiffener is indicated by said defining means for the size and style indicated when the sole is placed in position against said gage.

5. A device of the class described comprising a plate for supporting a shoe sole, means for defining the location of a shank stiffener carried thereby, members forming a guideway on said plate, a gage slidable in said guideway, there being a scale on said gage 90 and a series of reference lines on said guideway, said scale and said series of lines being adapted to cooperate so that when a sole is placed on said plate with its end in contact with said gage, the scale number and line 95 indicating, respectively, the size and style of said sole coinciding, said defining means correctly indicating the position of said shank stiffener for said sole.

In testimony whereof I have affixed my signature.

REINHARD E. BARTELS.
